REVERSIBLE SEAT

Raymond Burnham, Chicago, Ill., assignor, by
mesne assignments, to S. Karpen & Bros., a cor-
poration of Illinois

Application December 12, 1936, Serial No. 115,621

15 Claims. (Cl. 155—96)

This invention relates to a reversible seat particularly adapted for use in railway coaches and buses, but the invention may be usefully employed elsewhere.

5 An object of the invention is to provide an improved seat which can be readily reversed in direction and which will be laterally shifted during such reversal. Another object is to provide a reversible seat construction which is sturdy and operates smoothly without excess strain on any of its parts. A specific object is to provide a reversible seat in which a set of gears is utilized for laterally shifting the seat as it is rotated in reversal. Other specific objects and advantages 10 will appear as the specification proceeds.

A preferred embodiment of the invention is illustrated in the accompanying drawings in which—

Figure 1 is a plan view of the improved structure, the cushions and chair frame being omitted and the gears shown in dotted lines, this view indicating the position of the parts when the seat is in normal position; Fig. 2, a side elevational view, the cushions and chair frame being broken 20 away; Fig. 3, a vertical sectional view, the section being taken as indicated at line 3—3 in Fig. 1; Fig. 3a, a detail sectional view of the locking pin, the section being taken as indicated at line 3a—3a of Fig. 3; Fig. 4, a sectional view taken as indicated at line 4—4 of Fig. 2; Fig. 5, a vertical sectional view taken as indicated at line 5—5 of Fig. 1; Fig. 6, a sectional view taken as indicated at line 6—6 of Fig. 2, the supporting arms being shown in dotted lines, this view showing the parts 25 as they appear after the seat has started to rotate in reversal; Fig. 7, a view similar to Fig. 6, but showing the parts as they appear after the seat has rotated through 90°; Fig. 8, a plan view of a group of seat structures, the base of one of the seats being indicated in dotted lines, this seat being in normal position; Fig. 9, a view similar to Fig. 8, but showing the position of the seat after it has been turned through 45°; and Fig. 10, a view similar 30 to Fig. 8, but showing the position of the parts after the seat has been turned through 90°.

In the embodiment illustrated, A designates a base; B, a chair supporting member; C, mechanism for shifting the supporting member as it is rotated; and D, means for locking the supporting member in one of its lateral positions.

The base A may in general be of any suitable structure or material. In the form illustrated, it is rectangular in shape and has side walls 10 45 which are joined at their top with a flat top or

table 11. Centrally located in table 11 is a circular opening 12, and near its forward and rearward edges are grooves 13 extending from one side of the base to the other. Above table 11 is a plate 14 which rests flush on the surface of table 11 and has ridges 15 which engage grooves 13. At the side edges of plate 14 are the rails 16 and 17 which hold a top plate 18 slidably on plate 14. Top plate 18 is allowed to slide forwardly and rearwardly on plate 14 and plate 14 is allowed to slide laterally of table 11. As more clearly shown in Fig. 4, plate 14 is provided with a central opening 19 which is circular in form except for the apertured ear 20.

The frame supporting member B may comprise 15 front and rear arms 21 and 22 which are adapted to be fastened to the underside of the chair frame 60 by bolts 61 or other suitable fastening means. The hub 23, from which arms 21 and 22 extend, contains a central opening 24a in which a pivot 20 pin 24 is journaled. The underside of hub 23 is recessed and contains a ring gear 25 which is secured to hub 23 by keys 26. The outside walls of hub 23 rest upon top plate 18 of the base A and are in rotatable engagement with the top 25 surface of this plate. The lugs 63 and 64 on the outside of hub 23 engage rail 17 and act as stops to prevent rotation of member B beyond its normal or reversed positions.

The mechanism C for shifting the supporting 30 member comprises the pivot pin 24 which is received within opening 24a of member B and within opening 24b of top plate 18 and is rotatably engaged with both member B and top plate 18. Secured to pin 24 and above top plate 18 is a sun 35 gear 27 which has one-half as many teeth as does the ring gear 25. Planet gears or pinions 28 in toothed engagement with gears 27 and 25, have the lower ends of their shafts journaled in openings 29 of top plate 18, and have the upper ends 40 of their shafts journaled in a triangular bearing piece 30 which is in rotational engagement with pin 24.

At its lower end pin 24 is rigidly secured to an edge portion of the circular disk 31 which has 45 its edges in contact with the edges of opening 12 in table 11. The lower portion of pin 24 extends through opening 32 near the edge of circular disk 31 and is secured by nut 34 and washer 33, the nut serving to pull shoulder 35 of the pin firmly 50 against the top of disk 31. Other means of securing the pin may, of course, be used.

At the rotational center of disk 31 is an opening 36 which is adapted to receive the locking pin 37. Locking pin 37 extends through disk 31, 55

through hole 38 in plate 14, and through hole 39 in top plate 18. A reduced extension 40 of pin 37 extends into one of recesses 41 in the walls of hub 23. The lower portion of locking pin 37 is equipped with a heel 42 and a narrow fin 43 more clearly shown in Fig. 3a. Heel 42 is adapted to fit into socket 42a, and fin 43 is adapted to fit into the narrower socket 43a of the disk 31. A lever 44, which is pivotally connected 10 at 45 with the base A, is attached at its one end to the lower portion of locking pin 37 by connecting pin 46, and at its other end is connected with one end of treadle lever 47 by connecting pin 49. Treadle lever 47 extends through opening 49 in 15 the wall of base A and is fulcrumed at ears 50 on wall 10 by connecting pin 51. Pin 37 is urged upwardly into locking position by a spring 52 which bears against lever 44.

Operation

Fig. 8 of the drawings illustrates the seat as it appears in normal or forward position, and in this position the various parts of the structure are in the positions shown in Figs. 1 to 5 inclusive. It will be noted that stop 63 is resting against rail 17 and the chair 53 is facing squarely forwardly with its end 54 immediately adjacent the side of the coach; locking pin 37 extends upwardly through disk 31, through plates 14 and 18, and into recess 41 of hub 23, securely locking the chair against movement in any direction. When a passenger wishes to reverse the seat, he may depress treadle 47 with his foot. This operates through lever 44 to move pin 37 downwardly and out of engagement with hub 23 and plates 14 and 18, and leaves supporting member B and disk 31 free to rotate. It will be seen, however, that the seat is not unlocked and none of the parts are free to rotate until pin 37 has 40 been withdrawn completely from the hub 23 and both plates.

After the passenger has depressed treadle 47 and has unlocked the seat, he may turn the seat in the direction indicated by the arrow 56 in Fig. 8. As the seat begins to turn, and as clearly shown in Fig. 6, supporting member B is caused to be shifted toward the aisle and away from the side of the coach. Such lateral shifting movement allows the corner of the chair 53 to 50 pass the side of the coach and permits the chair to be moved as indicated in Figs. 9 and 10. As the chair is turned still farther it is shifted back again toward the side of the coach, and when completely reversed in direction, the end 55 of 55 the chair is immediately adjacent the side of the coach. When the chair has been completely reversed, the stop 64 impinges rail 17 and stops further rotation of the chair. Also at this position, upon release of treadle 47 by the operator, the locking pin 37 is urged upwardly by spring 60 52 into the openings in plates 14 and 18 and into recess 41 of hub 23 to firmly lock the seat in reversed position.

During the movement just described revolution 65 has taken place about two different centers. Supporting member has been rotating about pin 24, and pin 24 has been rotating with disk 31 about the center of the disk. An analysis of the 70 gearing connection will disclose that the rotation of member B about pin 24 is utilized to produce rotation of disk 31 to which pin 24 is eccentrically mounted.

Rotation of supporting member B about pin 24 in the direction of arrow 56 causes planet 75 gears 28 to rotate by reason of their engagement

with ring gear 25 secured to hub 23. Rotation of planet gears 28 in turn causes rotation of sun gear 27 and pin 24, but in a direction counter to arrow 56. Pin 24 is secured to disk 31 and prevented from turning except upon rotation also of disk 31. As disk 31 rotates in a direction counter to arrow 56, pin 24 is caused to move laterally and forwardly with respect to base A in the path of an arc of a circle whose center is the center of disk 31. Top plate 18, which receives pin 24, is also caused to move forwardly and laterally, and to do this plate 18 moves forwardly on plate 14 and between rails 16 and 17 and causes plate 14 to move laterally, the ridges 15 sliding in grooves 13. The ring gear 25 contains twice as many teeth as does the sun gear 27, so when the member B has been turned 45°, gear 27 has been turned through 90° and the forward travel of the pin 24 has reached a maximum, but the lateral movement of the pin will not have reached a maximum until member B has been turned through 90°. After the chair has been rotated through 90° and has reached the position shown in Fig. 10, further rotation causes pin 24 to be moved rearwardly and laterally back toward the side of the coach, and as rotation approaches 180° pin 24 is moving forwardly and laterally to its original position.

As the supporting member B and chair 53 has revolved through the 180° necessary for complete reversal, the pin 24 and consequently disk 31 has revolved through 360° or one complete revolution. Thus, it is seen that all parts of the structure, except the chair 53 and supporting member B are in identically the same position 35 at the end of reversal as they were when the chair was in normal position. Locking can take place only when the parts are in this condition, as the heel 42 and fin 43 of the locking pin 37 must fit into their corresponding sockets in disk 40 31, and also pin 37 must come into register with openings 38 and 40 of the plates 14 and 18. Until such a position is arrived at, the heel 42 of pin 37 will ride against disk 31 without being allowed to move upwardly into locking engagement.

An important advantage is gained by reason of the fact that the rotation of the pin 24 is counter to the rotation of the chair about the pin. As the chair begins to rotate from its normal position as indicated in Fig. 8, the end 54 50 is moved rearwardly with respect to pin 24. But as this takes place, pin 24 is being rotated and caused to move forwardly, so that with respect to the side of the coach the initial movement of the chair is lateral and longitudinal. This is important as it allows the chair to be removed from the side of the coach before the corners of the chair can strike.

In this embodiment the weight of the passenger and chair is borne by the supporting member B, 60 and transmitted through hub 23 through plates 18 and 14 to the bottom of base A. It is understood, however, that other supporting means may be used. For example, disk 31, of any suitable 65 form and suitably reinforced, may be centrally pivoted and rotatably supported within base A, and the weight of the chair may be transferred through pin 24 and disk 31 to base A.

The foregoing detailed description has been given for clearness of understanding only and no unnecessary limitations should be understood therefrom, but the appended claims should be construed as broadly as permissible, in view of the prior art.

I claim:

1. A reversible seat comprising a base, a chair supporting member movable about a pivot point, and rotatable means engaging said member for moving said pivot point in a circular arc having a center fixed with respect to said base, said means being effective to move said pivot point through one revolution as said member is moved through a half revolution. 5
- 10 2. A reversible seat comprising a base, a chair supporting member movable about a pivot point, and means engaging said member and said base for moving said point in a circular arc having a center fixed with respect to said base, said means being effective to rotate said pivot point at a speed double the rotational speed of said member about said point. 15
- 15 3. A reversible seat comprising a base, a pin movably supported by said base, a chair supporting member supported on said base and rotatably engaging said pin, said pin being journaled in said member, means engaging said member and said pin for rotating said pin with respect to said member as said member is rotated, and means for moving said pin laterally of said base as said pin is rotated whereby said chair supporting member is shifted in longitudinal as well as lateral directions as said pin is moved laterally on said base. 20
- 20 4. A reversible seat comprising a base, a pin movably supported by said base, a chair supporting member movably supported on said base and rotatably engaging said pin, said pin being journaled in said member, means engaging said member and said pin for rotating said pin through one revolution as said member is moved through one and a half revolutions with respect to said pin, and means for moving said pin laterally of said base as said pin is rotated whereby said chair supporting member is shifted in longitudinal as well as lateral directions as said pin is moved laterally on said base. 25
- 25 5. A reversible seat comprising a base, a pin movably supported by said base, a chair supporting member movably supported on said base and rotatably engaging said pin, said pin being journaled in said member, means engaging said member and said pin for rotating said pin at double the speed of rotation of said member about the axis of said pin, and means for moving said pin laterally of said base as said pin is rotated whereby said chair supporting member is shifted in longitudinal as well as lateral directions as said pin is moved laterally on said base. 30
- 30 6. A reversible seat comprising a base, a pin movably supported by said base, a chair supporting member supported on said base and rotatably engaging said pin, said pin being journaled in said member, means engaging said member and said pin for rotating said pin as said member is rotated, and a member rigidly engaging said pin and rotatable with respect to said base, said last-mentioned member being effective to move said pin laterally of said base as said pin is rotated whereby said chair supporting member is shifted in longitudinal as well as lateral directions as said pin is moved laterally on said base. 35
- 35 7. A reversible seat comprising a base, a pin movably supported by said base, a chair supporting member on said base and rotatably engaging said pin, said pin being journaled in said member, means engaging said member and said pin for rotating said pin as said member is rotated, and means for moving said pin laterally as said pin is rotated whereby said chair supporting member is moved longitudinally as well as laterally as said pin is moved laterally, and releasable locking mechanism for securing said member in selected positions. 5
- 40 8. A reversible seat comprising a base, a pin movably supported by said base, a chair supporting member on said base and rotatably engaging said pin, said pin being journaled in said member, means engaging said member and said pin for rotating said pin as said member is rotated, means for moving said pin laterally as said pin is rotated whereby said chair supporting member is moved longitudinally as well as laterally as said pin is moved laterally, and releasable locking mechanism for securing said member in selected positions, said locking mechanism being effective to secure said member in each of two positions 180° apart. 10
- 45 9. A reversible seat comprising a base equipped with a laterally slid able plate and a top plate forwardly slid able on said first-mentioned plate, a pin carried by said top plate, a chair supporting member slid ably supported on said top plate and rotatably engaging said pin, said pin being journaled in said member and in said top plate, means engaging said supporting member and said pin for rotating said pin as said supporting member is rotated, and means for moving said pin laterally of said base as said pin is rotated whereby said chair supporting member is moved longitudinally of the base as well as laterally thereof as said pin is moved laterally of the base. 15
- 50 10. Apparatus as set forth in claim 9 in which said first-mentioned means includes a gear wheel having its axis of rotation secured in said top plate. 20
- 55 11. A reversible seat comprising a base, a pin movably carried by said base, a chair supporting member supported on said base and rotatably engaging said pin, said pin being journaled in said member, means engaging said member and said pin for rotating said pin as said member is rotated, and a circular disk engaging said base at its edges and rigidly secured to said pin at a point removed from its center whereby as said pin is moved laterally, said chair supporting member is moved longitudinally as well as laterally of said base. 25
- 60 12. A reversible seat comprising a base equipped with a laterally slid able plate having an opening therein and a top plate forwardly slid able on said first-mentioned plate, a chair supporting member rotatably supported on said top plate and rotatably engaging a pin, said pin being journaled in said member and in said top plate and extending through the opening in said first-mentioned plate, said member and said pin each being equipped with a toothed gear, a pinion engaging said gears and having its axis of rotation secured in said top plate, said pinion being adapted to cause rotation of said pin when said member is rotated, and a circular disk having its edges in slid able engagement with said base and being rigidly connected with said pin at a point removed from its center. 30
- 65 13. Apparatus as set forth in claim 12 and including a spring-pressed locking pin extending through openings in said disk and plates for releasably locking said disk and plates in one position. 35
- 70 14. In a reversible seat of the character set forth, a base, a pin movably supported by said base, a chair supporting member rotatably en- 40
- 75 75

- gaging said pin, said pin being journaled in said member, said member and pin being equipped with toothed gears, and three pinions in engagement with the gears on said member and pin, said pinions being adapted to rotate said pin when said member is rotated but being incapable of rotation with respect to the axis about which said pin rotates whereby said chair supporting member is moved longitudinally and laterally of said base.
15. A reversible seat comprising a base, a pin rotatably movably supported by said base, a chair supporting member rotatably engaging said

pin, said pin being journaled in said member, means engaging said member and said pin for rotating said pin as said member is rotated about said pin, said means being adapted to rotate said pin in a direction opposite the direction of rotation of said member about said pin, and means for moving said pin laterally of said base as said pin is rotated whereby said chair supporting member is moved longitudinally as well as laterally of said base as said pin is moved laterally of said base.

RAYMOND BURNHAM.
